UNITED STATES PATENT OFFICE.

JOSEPH DANKS DAVIES, OF NATCHEZ, MISSISSIPPI.

PUMP.

SPECIFICATION forming part of Letters Patent No. 315,485, dated April 14, 1885.

Application filed May 1, 1884. (No model.)

To all whom it may concern:

Be it known that I, JOSEPH DANKS DAVIES, of Natchez, in the county of Adams and State of Mississippi, have invented certain new and useful Improvements in Pumps; and I do hereby declare the following to be a full, clear, and exact description of the invention, such as will enable others skilled in the art to which it appertains to make and use the same.

10 My invention relates to an improvement in pumps, the object of the same being to provide a pump which shall be differential—viz., one in which the amount of work accomplished shall be proportional to the pressure or head, 15 thus enabling the engine to drive it against any load, a further object being to prevent shocks from taking place in the pump from sudden changes of pressure either on the inlet or exit side of the piston.

20 With these ends in view my invention consists in certain features of construction and combinations of parts, as will be fully described, and pointed out in the claims.

In the accompanying drawings, Figure 1 is 25 a view in vertical longitudinal section through the pump and cushion-cylinder. Figs. 2 and 3 are views showing springs employed in place of the fluid or air cushion cylinder. Fig. 4 is a view in vertical section of the pump, showing 30 two cushion-cylinders connected thereto. Fig. 5 is a view on the line $x-x$ of Fig. 4; and Fig. 6 is a view on the line $y-y$ of Fig. 5, the pipe O , which is omitted in Fig. 5, being shown.

35 a represents a pump-cylinder fitted as usual with a piston or plunger, B , which is attached to an operating-rod, A ; a' is another cylinder of any approved size, situated conveniently in close proximity to and parallel with the 40 cylinder a . The cylinders a and a' communicate with each other at both ends. The cylinder a' is provided with a piston, B' . A third cylinder, a^2 , is preferably situated longitudinally opposite the cylinder a' , and rigidly 45 secured thereto by means of bolts n or other suitable means. The cylinder a^2 is provided with a piston, B^2 , the latter being connected with the piston B' by a connecting-rod, b , passing through the adjacent ends of the cylinders a' and a^2 , which ends of the cylinders are held a sufficient distance apart to admit 50 the proper stuffing-boxes. The cylinder a is

provided with the exit-valves c c' , and the cylinder a' with the inlet-valves d d' . The cylinder a^2 , which may be conveniently termed 55 the “cushion-cylinder,” is provided with the inlet-valves e e' and with the safety-valves F F' . The cylinder a^2 is further provided with the feed-pipes H H' , one of which may conveniently feed liquid and the other gas or 60 steam.

The operation of the pump is as follows: Suppose the valves c c' d d' e e' F F' to be closed, the cylinders a a' full of water, and the cylinder a^2 filled with air, gas, steam, liquid, 65 or a mixture of liquid and air or gas. Let the three pistons be in the position shown in Fig. 1. Suppose, now, power to be applied to the rod A , forcing the piston B in the direction shown by the arrow. The piston B' 70 will be thereby forced in the opposite direction, and will carry with it the piston B^2 in the cylinder a^2 . The air not being able to escape from a^2 until the pressure is sufficiently great to lift the safety-valve, the piston B^2 75 will accumulate pressure before it and tend to produce a vacuum behind it until the said piston nearly or quite comes to a standstill, when the pressure before the piston B in a will become sufficiently strong to lift the exit-valve c and deliver water therefrom. At this same moment there is produced a sufficient vacuum behind the piston B to open the inlet-valve d' , which now admits water. B now starts on its return. The expansive 80 force of the gas or air, compressed by the previous motion of the piston B^2 , will now be given back to the piston B . As the piston B^2 moves in the return motion, the air in the cylinder a^2 is again compressed before it and 85 a partial vacuum formed behind it until it again comes to a standstill. Just before it comes to a rest, the pressure in the cylinder a becomes sufficiently great to open the valve c' , and water is delivered at the same moment 90 the valve d is opened by the partial vacuum formed, and water enters the pump. When the piston B^2 arrives at mid-stroke, it is in equilibrium as far as the pressure in the cylinder a^2 is concerned, but will continue to 95 move on account of its own momentum and the pressure on the piston B' until the compressed air before it causes it to stop.

The dropping of the valves c c' may take

place as soon as the pistons B' and B^2 stop, or as soon as the return motion of the piston B releases the pressure and allows the air in a^2 to regain its equilibrium.

- 5 i represents an air-chamber in connection with the cylinder a . It is provided with a cut-off valve, K , to shut the air in the chamber off from the cylinder a whenever desired. It is found advantageous to do this when starting the pump. The air-chamber i may or may not be used in connection with the cylinder, or there may be two air-chambers, one at each end of the cylinder.

There may be cut-off valves also, arranged 15 between the cylinders a and a^2 to throw the latter out of communication with the former whenever desired.

As before stated, the pipes $H H'$ may lead 20 gas and liquid, respectively. Now, it is obvious that the more liquid in combination with the gas the less will be the movement of piston B^2 , the pressure from piston B remaining constant. Again, the curve of force transmitted may be varied by either of the following 25 methods—viz., first, by increasing the pressure; secondly, by changing the relative sizes of the cylinders a a^2 ; and, thirdly, by the amount of clearance in a^2 . These several 30 changes give results represented by different portions of the hyperbolic curve of expansion of gases. It will be seen, therefore, that different pressures required to pump against cause 35 the amount of delivery to be in proportion to the pressure.

In place of the expansion of gases a spring 40 may be used in the cylinder a^2 , as shown in Figs. 2 and 3. With straight connections the effect will now be invariable; but if a volute 45 or elliptic spring, S , be used, as represented, and the center connection, B^2 , be made so that it can move more or less before catching the spring S , the differential will be modified.

In Figs. 4, 5, and 6 the cushion-cylinder is 50 made in two parts, $f f$, pivoted to a suitable frame by its hollow trunnions o . Each cylinder f is provided with a piston and piston-rod, the outer ends of which latter are connected by the flanged collar t to the rod b . The hollow trunnions of both of these pistons 55 are connected to the steam, air, or water supply pipe O , provided, preferably, at a point outside of both hollow trunnions with a check-valve, o' , adapted to prevent the escape or back-flow of the gas or water. The ports o^2 of the 60 hollow trunnions terminate at or near the inner or adjacent ends of the cylinders f , so as to admit the actuating-fluid in front of both pistons. When the pistons are in equilibrium, as shown in Figs. 4 and 5, the pistons of the cylinders f rest at the limit of their outward movement. As soon, however, as the pressure 65 in the cylinder a' is sufficient to move the piston B' in either direction, both cylinders turn on their trunnions, and the pistons thereof are drawn toward the inner or adjacent

ends of their respective cylinders and form the cushions.

It is evident that numerous slight changes in the construction and relative arrangement 70 of the several parts might be resorted to without departing from the spirit of my invention, and hence I would have it understood that I do not confine myself to the exact construction shown and described, but consider myself at 75 liberty to make such changes as fairly fall within the spirit and scope of my invention.

Having fully described my invention, what I claim as new, and desire to secure by Letters Patent, is—

1. In a pump, the combination, with a main cylinder having outlet-valves and a piston, and an auxiliary cylinder provided with a piston and supply-valves in communication with the main cylinder, of a cushion-cylinder 85 connected with the piston in said auxiliary cylinder by a piston-connecting rod, substantially as set forth.

2. In a pump, the combination, with a main cylinder having outlet-valves and operating- 90 piston, and an auxiliary cylinder in communication with the main cylinder and provided with a piston and supply-valves, of a cushion-cylinder having its axial line on the prolongation of the axial line of the said auxiliary cylinder, 95 said cushion-cylinder being connected with the auxiliary cylinder by an independent piston-connecting rod, substantially as set forth.

3. In a pump, the combination, with a main 100 cylinder having outlet-valves and an operating-piston, and an auxiliary cylinder provided with supply-valves and a piston in communication with the main cylinder, of a cushion-cylinder provided with valves for admitting 105 air, gas, or liquid, and a rod connecting the piston in the auxiliary cylinder with a piston in the cushion-cylinder, substantially as set forth.

4. In a pump, the combination, with a main 110 cylinder having outlet-valves and an operating-piston, and an auxiliary cylinder having supply-valves in communication with the main cylinder, of a cushion-cylinder provided with check-valves for alternately admitting and 115 preventing the escape of air, gas, or liquid, and further provided with safety-valves and a rod connecting a piston in the auxiliary cylinder with a piston in the cushion-cylinder, substantially as set forth.

5. In a pump, the combination, with a main 120 and auxiliary cylinder having their axial lines parallel and communicating directly with each other, the main cylinder being provided with a piston and two delivery-valves, and the auxiliary cylinder with two supply-valves, of a cushion-cylinder situated longitudinally opposite the auxiliary cylinder, and a rod connecting a piston in the auxiliary cylinder with a piston in the cushion-cylinder, substantially 125 as set forth.

6. In a pump, the combination, with a main

cylinder provided with suitable supply and delivery valves and operating piston, of one or more air-chambers communicating with the main cylinder, and devices for shutting off the 5 air-chambers from the cylinder at pleasure, substantially as set forth.

In testimony whereof I have signed this

specification in the presence of two subscribing witnesses.

JOSEPH DANKS DAVIES.
